UNITED STATES PATENT OFFICE.

SAVA ROGOZEA, OF PARIS, FRANCE.

CARTRIDGE.

1,246,660.

Specification of Letters Patent. Patented Nov. 13, 1917.

Application filed April 6, 1915. Serial No. 19,476.

To all whom it may concern:

Be it known that I, SAVA Rogoza, a citizen of the Republic of France, residing at Paris, 91 Boulevard St.-Germain, in the Republic of France, engineer, have invented certain new and useful Improvements in Cartridges, of which the following is a specification.

This invention relates to improvements in firearms and more particularly to the cartridges to be used with such arms, and has for its object to provide firstly a cartridge the projectile or ball of which is adapted to acquire in passing through the barrel of the arm rotation around its axis even when such barrel is not rifled; secondly, to provide a cartridge, the projectile or ball of which is loaded with powder and so fitted to the cartridge that the charges of powder of the cartridge and ball will burn gradually and in opposite directions during the travel of the projectile or ball through the barrel; thirdly, to provide a projectile or ball adapted to produce on falling peculiar effects of rebounding and level shooting as will be more particularly described herein-after; and fourthly, to provide a cartridge showing divers peculiarities of construction which will be referred to further on and with reference to the accompanying drawings, in which:

Figure 1 is a partial longitudinal section of an arm according to this invention, a part of the barrel or cannon being broken away.

Fig. 2 is an elevation of the projectile of Fig. 1, the outer jacket and the priming element on the point of the ball not being shown.

Fig. 3 is a transverse section of the projectile on the line A—A of Fig. 1, such projectile being provided with its jacket.

Fig. 4 is a longitudinal section of another embodiment of this invention, certain parts of the projectile being shown in elevation, and

Fig. 5 is a partial section on a larger scale of the projectile shown in Fig. 4.

The bore of the barrel or cannon has two cylindrical parts 1 and 2 (see Fig. 1) of different diameters and a slightly tapered part 3 between the aforesaid parts, the reduced cylindrical part 2 being placed at the mouth and being relatively short. The cannon is furthermore reinforced from the mouth and a represents the cartridge and b

the projectile or ball. The cartridge a is made up of an outer socket 5 adapted to be adjusted in the breech-end of the cannon, of an inner socket 5^a, adjusted in the socket 5, of a central tube 6 secured to the bottom of the socket 5^a, a charge of powder 7 filling the cartridge, save the inner tube 6, and a priming element 8 being placed in the outer orifice of such tube.

The projectile or ball b comprises a cylindrical body 9 and a reduced forward part 10 terminating in front, in an ogive or conical point 11, also provided with a little cylindrical prolongation 12, these parts 9, 10, 11, 12 being preferably made in a single piece, but which may be made in several pieces assembled by screws or otherwise.

Within the projectile or ball are provided two chambers 13 and 14, separated from one another by a transverse partition 15, in which are provided several narrow channels 16, and in the back chamber 13 is secured a central tube 17 the inner end of which is closed while the outer end is open.

In the periphery of the body 9 of the projectile or ball are provided helical channels 18 which open at the two ends of such body, and which are covered laterally by a jacket 19 adjusted on the said body; the rear of such jacket passes a little beyond the body and is adapted to be adjusted in the orifice of the socket 5^a.

The transverse section of the channels 18 decreases preferably from the rear end to the forward end.

In the surface of the jacket 19 are provided circular grooves 19^a, in which are secured the rings 20 made of soft metal, such as copper, tin and the like, the outer diameter of which is intermediate between the inner diameters of the parts 1 and 2 of the barrel or cannon. When the projectile passes into the part 2, such rings are crushed to some extent and thus guide the projectile without any play in the last part of the barrel.

Slidable on the reduced part 10 of the projectile or ball is a conical ring 21, the rear face of which is adapted to come and stop up the front orifices of the channels 18, and of which the forward face is enabled to come and impinge against a shoulder 22 provided on the part 10.

A charge of powder 23 is placed in the tube 17, and explosives 24, 24^a are placed in

the chambers 13 and 14. Lastly a priming element 26 is placed on the extension 12 through which is bored, as well as through the point 11, a central channel 27 for the purpose of firing the charge 24^a.

On the flaming up of the priming element 8 in the usual manner, the gases passing through the tube 6 light up the forward part of the charge of powder 7 of the cartridge and the rear part of the charge 23 of the projectile or ball. The projectile or ball is then moved forward by the pressure of the gases given off, and at the same time a part of such gases passes through the channels 18 and escaping forward between the ring 21 and the inner wall of the barrel or cannon, produce on the helical walls of the channels 18 a pressure which causes the ball to revolve around its axis. During the combustion of the propulsive charges 7 and 23, which spreads in inverse directions in both charges, the two flames, impinge against one another and this insures the complete combustion of the smoke; furthermore, experience has shown that the recoil is very much reduced.

When the projectile or ball comes to the mouth of the barrel, the rings 20 are somewhat crushed against the part 2 of the bore 30 as aforesaid, and this insures the guidance of the ball; at the same time the escape of the gases around the ball ceases and the result is that there is an increase in the pressure of the gases which continue to be given off from the charges 7 and 23, the latter being so determined that they burn until the ball escapes from the cannon. This increase of pressure is favorable to the range of the firing.

When the projectile or ball leaves the cannon, the resistance of the air brings the ring 21 back, so that the latter obstructs the channels 18 and prevents the air from passing through the latter without any tendency either to stop or to reverse the rotation of the ball. The result is that the speed of rotation imparted by the passage of the explosive gases in the channels is not substantially reduced by the resistance of the air which only acts on the peripheral circular surface of the ball.

When the projectile or ball hits an obstacle, the priming element 26 is put in flames and fires the charges 24^a and 24, 55 which produces the bursting of the ball.

In the embodiment shown in Figs. 4 and 5, the socket of the cartridge comprises a part 5 adapted to be adjusted in the breech-end of the cannon and a reduced part 5^b; 60 the annular space comprised between such part 5^b and the central tube 6 secured at the bottom of the socket is relatively narrow and is filled with the powder 7. Furthermore, the rear end of the projectile or ball 65 is open, the body 9^a being slideable on the

reduced part 5^b of the socket and the central tube 17 secured at the center of the ball is slideable within the tube 6. The play provided between these tubes is great enough to allow of the combustion gases given off 70 by the powder charge 23 of the tube 17 passing readily between the two tubes and firing the powder 7 between the tube 6 and the socket 5^b.

With such an arrangement, the flame of 75 the priming element 8 lights directly the charge 23 and the combustion of the latter fires the charge 7, which burns gradually on account of its great length and its small transverse section; the amount of powder in 80 the socket and in the projectile or ball is moreover so determined that it will burn completely before the projectile or ball escapes from the cannon.

The point 11^a of the projectile or ball is 85 distinct from the reduced part 10^a and is connected therewith by pins 28 which are relatively brittle. The interior of the chamber 14^a provided in the forward part of the ball is divided by two washers 29 and 30 into 90 three chambers, the intermediate one which incloses the small balls 31 and the two other chambers inclose the explosive charges 24^b and 24^c, which are put in communication by a central tube 32 inclosing the slow combustion powder 24^a; such tube 32 is secured to the washer 29 and passes loosely through the washer 30; its rear end is preferably closed and its wall, near such end, is provided with small holes 32^a.

26 designates the priming element which caps the extension 12^a of the point 11^a; such element is held in place by a capping-piece 33 made of fabric which covers the point and which is secured by means of a connection 34 which encircles the capping-piece and engages in the groove 35 provided in the point 11^a. Before the projectile is inserted in the cannon, the priming element 26 may still be protected by a metal or other cap 110 which is frictionally engaged on the point 11^a or the part 10^a of the ball; such cap is taken off when the projectile is inserted in the cannon.

When the projectile or ball hits an obstacle, it will put in flames the priming element 26, which in its turn will put in flames the explosive 24^c. The explosion of the latter will drive back all the part of the projectile or ball which lies behind the point 11^a, 120 and will break the pins 28. The fire will then be transmitted slowly by the powder 24^a to the explosive 24^b; and lastly the explosion of the latter will drive outwardly the washers 29, 30, the tube 32 and the balls 31. 125

The dimensions and proportions of the projectile or ball are so determined that its center of gravity lies beyond the middle of its length, for the purpose of being sure that the ball after being shot upwardly and more 130

or less obliquely will always fall with the point downward, and that on a falling trajectory almost vertical.

The result is that in touching the ground or other impediment, the ball produces a first explosion which will send it up a few yards, save its point which will remain on or in the impediment. The projectile or ball will fall on the ground and will place itself substantially flat in any direction. Then the explosion of the charge 24^a will drive the parts 29, 30, 31, 32 nearly horizontally in one direction and the remaining parts 10^a, 17^a of the projectile or ball will be driven in the reverse direction.

The numerals 18, 19, 20, 21 of the Figs. 4 and 5 designate the same parts as those of the Figs. 1 to 3.

Of course, the different arrangements above described are only given as examples and may be greatly varied without changing the essential characters of the invention. It must also be understood that the invention is applicable to fire-arms of all calibers.

25 Claims:

1. A projectile or ball having in its wall helical channels open at both their ends, and means whereby to prevent such channels from being traversed by the air of the atmosphere during the journey of the ball.

2. A projectile or ball having a large cylindrical portion and a reduced cylindrical portion, such large portion being provided with helical channels which open at the rear and the forward part of the said portion, and a ring slideable on such reduced portion of the ball and adapted to obstruct the forward orifices of such helical channels.

3. A projectile or ball having helical

grooves in its periphery, a cylindrical jacket 40 surrounding such ball and closing laterally such grooves, so that the latter form helical channels open only at the rear and the forward ends, and means whereby to prevent such channels from being traversed by the 45 air of the atmosphere during the journey of the ball.

4. A cartridge comprising a socket, a projectile or ball adjusted to the forward part of the socket, charges of powder in the 50 socket and in the projectile or ball respectively, and means whereby to fire the charge of the socket at a point, located at the forward part of the latter and at the same time to fire the charge of the projectile or ball 55 at a point located at the rear of the said projectile or ball.

5. A cartridge comprising a socket, a projectile or ball adjusted to the forward part of the socket, a central tube secured to the 60 bottom of the socket and extending forwardly, a charge of powder in the socket around such tube, a charge of powder in the projectile or ball wholly in front of the charge 65 of the socket, and means whereby to fire such charges of powder through the said tube whereby the combustion will spread from the forward part to the rear in the socket and from the rear to the forward part in the 70 projectile or ball.

In testimony that I claim the foregoing as my invention I have signed my name in presence of two subscribing witnesses.

SAVA ROGOZEA.
